UNITED STATES PATENT OFFICE.

FRANCIS A. VAUGHN, OF MILWAUKEE, WISCONSIN.

DESIGN FOR A LIGHT-FIXTURE.

51,085.

Specification for Design.

Patented July 24, 1917.

Application filed February 17, 1917. Serial No. 149,363. Term of patent 14 years.

To all whom it may concern:

Be it known that I, FRANCIS A. VAUGHN, a citizen of the United States, residing at Milwaukee, in the county of Milwaukee and State of Wisconsin, have invented a new, original, and ornamental Design for a Light-Fixture, of which the following is a description, reference being had to the accompanying drawing, forming part thereof.

Figure 1 is a side view of a light fixture showing my new design; and

Fig. 2 is a top view of the bowl and bracket, the supporting tube being shown in section.

I claim:

The ornamental design for a light fixture, as shown.

FRANCIS A. VAUGHN.

Witnesses:

MARIE GRAY,
CHARLOTTE G. PREUSS.
